UNITED STATES PATENT OFFICE.

DONALD J. CAMPBELL, OF MUSKEGON HEIGHTS, MICHIGAN.

AUTOMATIC-EXHAUST-VALVE CONSTRUCTION.

Application filed February 28, 1921. Serial No. 448,720.

To all whom it may concern:

Be it known that I, DONALD J. CAMPBELL, a citizen of the United States of America, residing at Muskegon Heights, in the county of Muskegon and State of Michigan, have invented certain new and useful Improvements in Automatic-Exhaust-Valve Constructions; and I do hereby declare the following to be a full, clear, and exact description of the invention, such as will enable others skilled in the art to which it appertains to make and use the same.

This invention relates to an automatic air release valve for use in connection with compressed air mould forming machines, one type of which is shown and described in a copending application for patent filed by me having Serial Number 443,739, filed Feb. 10, 1921, and in which sand is forced by the impulse of compressed air from a hopper into the mould or mould box so as to fill the mould and compress the sand to the required density. In doing this, the sand containing hopper is clamped between an upper valve casing through which the air is carried to the upper end of the hopper and a mould box located below the hopper so as to preclude the escape and waste of the air, slight vents being provided, however, that when the air has done its work of compressing the sand into the mould box, and the supply above is cut off, the pressure in the hopper will slowly decrease. This in time would free the hopper and the mould box for further operations therewith, but in order to save time, it is desirable that this exhausting of the air pressure shall be more rapid. At the same time, the exhaust of the pressure must not interfere with the workings of the pressure of the air during the time that the mould is being made.

It is a primary object and purpose of the present invention to provide the machine with an automatic exhaust valve which is inoperative for that purpose during the time that the mould is being formed, but which becomes automatically operative as soon as the working pressure is cut off and some escape of the air and reduction of the pressure has taken place in the hopper, thereupon bringing the exhaust valve openings into play to allow the rapid reduction of the pressure and freeing of the parts of the machine for the necessary movements thereof and without loss of time as would otherwise occur. A

further object of the invention is to make this valve of very simple character, of few parts, and so that it will always be effective and substantially certain to stay in order in spite of the severe conditions under which it is used.

Many other objects and purposes than those stated will also appear as understanding of the invention is had from the following description, taken in connection with the accompanying drawing, in which,

Fig. 1 is a central vertical section through the upper part of the sand hopper and co-operating valve casing, my invention of automatic exhaust valve being applied thereto.

Fig. 2 is a fragmentary vertical section showing the parts of the valve in another position than that occupied in Fig. 1.

Fig. 3 is a side elevation of the expanding perforated sleeve which forms one element of the exhaust valve construction.

Fig. 4 is a vertical transverse section on the plane of line 4—4, of Fig. 1, and

Fig. 5 is a similar section on the plane of line 5—5, of Fig. 1.

Like reference characters refer to like parts in the different figures of the drawing.

The sand hopper with which my invention is used is shown at the upper part thereof, at 1, being provided with an out-turned annular flange at its upper end. A valve casing 3 is located over the hopper in the operative position of the parts, and intermediate its upper and lower ends, is formed with a transverse horizontal web 4 in which an opening is made for air passage, this opening at its upper side being fashioned as a valve seat. The under side of the valve casing is covered by a plate 6 inset into the flange 5 made around the lower end of the valve casing, and secured thereto by screws 7. A rubber ring gasket 8 is retained between the edges of the plate and the outer depending portions of the flange 5 as shown. A number of openings 9 are made in the plate 6 in which short tubes 9 are secured, the same being directed at the proper angle to align with the sand passages in the hopper as appear in the copending application for patent thereon.

A valve 10 is normally seated in the opening made through the web 4, having a rod 11 attached thereto which extends upward through a second transverse web 12 and a stuffing box 13 above the same, this web

being cast integral with a substantially cylindrical sleeve 14 which is attached at its upper end to a suitable overhead beam 15, forming a part of the moulding machine, and at its lower end is provided with an outwardly annular flange 16, matching and connecting with a similar flange 17 at the upper end of the valve casing 3. Compressed air is led into the chamber made by the webs 4 and 12 and the sides of the valve casing 3 and sleeve 14 between said webs by an inlet pipe 18. Rod 11 at its upper end has attachment to a block 19 which is pivotally connected at 20 with the inner end of a lever 21 which extends through a slot in a side of the sleeve and is pivotally mounted between its ends at 22 on lugs 23 cast integral with and extending outwardly from the sleeve. A coiled spring 23^a is disposed between the beam 15 and the upper side of the inner end of lever 21, tending to hold the valve 10 in closing position.

The valve casing at one side below the web 4 has a cylindrical projection 24, somewhat enlarged at its outer portion as indicated at 24^a and interiorly bored for the reception of the moving parts of the valve mechanism of my invention. A passage 25 connects the interior of the lower portion 30 of the valve casing 3 with the larger opening bored in projection 24. A series of openings 26 are made in the walls of the part 24, spaced apart around the same as shown.

Within projection 24 a plug 27 is located, the same having a slightly enlarged head 27^a to fit the larger outer boring in the larger outer section 24^a and acting to limit the movement of the plug inward. A sleeve of metal 28 is attached to and extends inwardly 40 from the plug, this sleeve being divided at one side, as indicated at 29, whereby the same may expand, as will later appear. A series of spaced apart openings 30 are made in the sides of sleeve 28 and are adapted to align with the openings 26 when the plug 27 is at its inner position as shown in Fig. 1.

An exteriorly threaded plug 31 is threaded into the end of the enlarged portion 24^a of said projection 24 and is equipped at its outer side with a head 32 whereby the same may be readily turned by a wrench or like implement. A strong coiled spring 33 is interposed between the two plugs 27 and 31, the effect of which is to normally force the first plug 27 to inner position to bring openings 26 and 30 into alignment. In order that the plug 27 shall not turn and thus disturb the alignment of the openings, a pin 34 is connected to the projection 24 at the inner shoulder between the larger and smaller borings therein and seats in a recess 35 in the edge of the part 27^a of the plug. It is evident that the tension of the spring 33 may be regulated by adjusting the second plug 31 to different positions. In practice,

I prefer to more or less cover the openings at 26 by a surrounding spaced apart flange 36, as shown in Figs. 1 and 2, the same protecting the openings against the entrance of sand particles or dirt, and also directing the air exhausted outwardly in a common direction, not permitting it to pass outwardly in a number of directions radially as would be the case if the flange was eliminated.

In the operation of the exhaust valve mechanism, when sand is to be forced from the hopper into the mould box or flask, the handle 21 is operated in a downward direction, lifting valve 10 and permitting passage of the air into the lower part of the valve casing 3, below web 4 and thence through the tubes 9 into the hopper. At the same time the full pressure of the air is carried through passage 25 against the inner end of the plug 27 and into the sleeve 28, the pressure against the inner sides thereof expanding it and forcing it tightly against the sides of the member 24. The pressure is great enough to overcome the force of spring 33, whereupon the plug 27 with attached sleeve is moved outwardly to the position indicated in Fig. 2, openings 30 moving away from the openings 26 so that no air can escape. This insurance against the escape of air is aided by the expansion of the sleeve 28 and its pressure against the walls of the projecting part 24. The lifting of the valve 10 is momentary, only long enough for the air to force the sand from the hopper, after which the handle 21 is released, valve 10 immediately closing. The relief vent, above noted, in the plate between the lower end of the hopper and the mould box into which the sand is forced, said plate being the subject matter of a separate application for patent, relieves the pressure of the air in the hopper, the sand being porous and the air passing therethrough. This relief soon reduces the pressure sufficient that spring 33 moves the sleeve 28 and attached plug back to its initial position, shown in Fig. 1, the openings 26 and 30 aligning, and the air exhausting very rapidly as is evident. Accordingly, in a very short time, almost instantly, the air pressure in the hopper is reduced to that of the atmosphere outside, and the hopper may be moved away from the valve casing 3 for the reception of additional sand.

The construction of automatic exhaust valve is very simple yet effective for the purposes for which it is designed. Its parts are durable and not liable to get out of order. The spring tension may be varied as desired for different conditions in a particularly simple and effective manner. The appended claims define the invention and I consider myself entitled to all forms of structure coming within their scope.

I claim:

1. In a device of the character described, a valve casing adapted to receive air under pressure, said casing at one side having a projecting portion interiorly bored for part of its length, the outer portion of the boring being of larger diameter than the inner portion, and said inner portion having a plurality of communicating openings through the side of the said projecting portion, a plug loosely mounted within said projecting portion and having an enlarged outer head, a split sleeve attached to the inner end of the plug having a plurality of openings through the side thereof which come into alinement with the first mentioned openings when the plug is in inner position, means for holding the plug from rotary movement, a second plug threaded into the outer end of said projecting portion, and a strong compression spring disposed between the two plugs, substantially as described. 50
2. In a device of the character described, a valve casing adapted to receive air under pressure, said casing at one side having an exhaust valve construction associated therewith, comprising a movable member having a series of openings therethrough, a surrounding member therefor having a cooperating series of openings normally alining therewith, means for yieldingly holding the movable member in such position that said openings are in alinement, and a passage leading from the interior of the valve casing to carry the compressed air against the movable member to move the same to carry the openings out of alinement, the same remaining out of alinement while the force of the compressed air is fully exerted against the movable member but returning to original alinement on escape of and reducing of a portion of the air pressure in the valve casing, substantially as described. 55
3. In a device of the character described, a valve casing adapted to receive air under pressure, said casing having an outlet passage at one side thereof, and being provided with an interiorly bored projecting portion
4. In a device of the character described, a casing adapted to receive air under pressure, said casing having an outlet passage at one side and an interiorly bored projecting portion into which said passage leads, said projecting portion having openings through its sides, a plug loosely mounted within said projecting portion, a split sleeve attached to the inner end of the plug, said sleeve having a plurality of openings registering with the openings in said projecting portion when the plug is in its extreme inner position, means for stopping the plug at such position that the openings register, means for holding the plug from rotation, and strong spring means normally forcing the plug to inner position. 60
5. In a device of the character described, a casing adapted to receive air under pressure, said casing having an outlet passage at one side thereof and an interiorly bored projecting portion into which said outlet passage leads, said projecting portion having openings through its sides, a plug loosely mounted within said projecting portion, an expandible sleeve attached to the inner end of the plug, said sleeve having a plurality of openings registering with the openings in said projecting portion when the plug is in its extreme inner position, spring means normally forcing the plug to said inner position, and means for adjusting the pressure of said spring means, substantially as described. 65

In testimony whereof I affix my signature.

DONALD J. CAMPBELL. [L.S.]
